UNITED STATES PATENT OFFICE.

FRANK C. DREW, OF SAN FRANCISCO, CALIFORNIA.

SIGNAL FOR MOTOR-DRIVEN VEHICLES.

Application filed January 19, 1923. Serial No. 613,568.

To all whom it may concern:

Be it known that I, FRANK C. DREW, a citizen of the United States, residing in the city and county of San Francisco, State of California, have invented a new and useful Signal for Motor-Driven Vehicles, of which the following is a specification.

My invention relates to a novel construction and arrangement of a signaling device, 10 by the use of which a definite direction, either straight ahead, or to the right or to the left, or to a stop, may be shown by the driver of a motor-driven vehicle to any other driver of another following motor-driven vehicle or pedestrian.

My invention is an improvement upon an invention which forms the subject-matter of my application for patent filed December 20, 1922, as Serial No. 607,926, and its object is 20 the construction of certain improvements in the mechanism by which I control the signal hand or indicating device which forms a part of the subject-matter of my previous invention and is illustrated in Figure 11 of 25 this application.

In common with the invention of my previous application, a general object of this invention is the provision of novel means to effectuate the control of the signaling device, so that the proper signal shall be shown, and to such ends my invention comprehends certain specific means for the controlling of the different positions of the signaling device, and also other novel features of construction which will hereinafter more clearly appear in the detailed description of my invention.

For the purpose of illustrating my invention, I have in the accompanying drawings 40 illustrated certain forms thereof which are at present preferred by me, since in practice they will give satisfactory and reliable results. It is to be understood, however, that the various instrumentalities which my invention embodies may be variously arranged and organized and that my invention is not, therefore, limited to the precise arrangement and organization of these instrumentalities as herein shown and described.

50 In the drawings, Figure 1 represents a fragmentary, diagrammatic, side elevation of a motor vehicle embodying my present invention.

Figure 2 represents an elevational view 55 taken in the direction of the arrow 2 on

Figure 1, of the signal-operating mechanism of my present invention, which is mounted on the steering column.

Figure 3 represents a side elevation of the mechanism represented in Figure 2. 60

Figure 4 represents on an enlarged scale a vertical sectional detail on the line 4—4 of Figure 2, of the housing mechanism illustrated in Figures 2 and 3.

Figure 5 represents a rear elevation of the 65 button housing and its adjuncts removed from the carrying plate.

Figure 6 represents a sectional plan on the line 6—6 of Figure 5.

Figure 7 represents a sectional plan on the 70 line 7—7 of Figure 5.

Figure 8 represents a sectional plan on the line 8—8 of Figure 5.

Figure 9 represents an elevation of the 75 button plate illustrated in Figures 5 to 8, removed from the button housing.

Figure 10 represents a supporting bracket with respect to which the signal hand is mounted.

Figure 11 represents an elevation illustrating the mounting of the signal hand, and in dotted lines its placement in different 80 positions.

Similar numerals of reference indicate 85 corresponding parts.

Referring to the drawings.

1 designates a typical framework or body of a type of motor vehicle,—a rear portion 2 of which preferably supports my signal device proper, while a steering column 3 90 typifies any usual form of steering shaft.

Referring to Figure 11,—4 designates a signal hand which is the signaling device proper of my present and also of my former invention, and which by being mounted 95 upon a right angularly extending fixed axis 5 central with the palm of the hand, is adapted to be deflected into different directions as illustrated in full lines and in dotted lines in Figure 11, to indicate to 100 following vehicles the intended direction of movement or the stoppage of the machine which carries my signal.

6 designates a casing which supports a connector wheel 7 and from which extends 105 a sleeve 8 through which passes a flexible connector 9 which itself passes through a hollow flexible sheath 10, which, as illustrated in Figure 1, is carried forward to the signal-operating mechanism on the 110

steering column, all as explained in my pending application for patent and therefore requiring no detailed explanation in this application.

5 It may be observed that the signal hand need not necessarily be placed at the rear of the vehicle, but may, if desired, extend laterally from the body at a point intermediary of its length, always, however, at 10 such point as to be visible at the rear of the vehicle.

The construction and mounting of the signal hand 4 as typically illustrated in Figure 11, being essentially the same as in 15 my pending application, a description of it need not be repeated in this application.

My novel control mechanism for operating the signal hand through the intervention of the flexible connector 9 and sheath 20 10, is illustrated in outline in Figure 1 and in detail in Figures 2 to 9 inclusive, and is of the following construction:—

Connected with the steering column 3 by any preferred means but conveniently by 25 clamping clips 11, is a carrying plate 12 upon which the button housing 13 is mounted and adapted to be moved up or down so as to impart an end for end movement to the flexible connector 9, and through it operate the connector wheel 7 which in turn 30 operates the signal hand. The button housing 13, like a similar element in my pending application, is the device by means of which the flexible connector 9 is moved, 35 and the housing itself is in the form of a block the detailed construction of which is particularly shown in Figures 4 to 8 inclusive, and which is provided with a thumb piece 14, by means of which when 40 the housing is released for movement it is adapted to be moved upwardly or downwardly.

It being, as explained, the intention of 45 my invention to provide means for moving the housing upwardly and downwardly, it is as in my former invention, necessary to provide means for automatically locking the housing in its uppermost position and for stopping it at given positions in its downward movement, so that through the flexible connector the signal hand may be placed with relation to its axis 5 in any one of the desired positions indicated in Figure 11.

The locking device which maintains the 50 housing in its uppermost position is that shown in Figures 1, 2, 3 and 4, and is preferably of the following construction:—

A latch plate 15 is pivoted on a pivot 55 rod 16 which is transversely mounted in the housing 13 and passes loosely through ears 17, see Figures 4 and 6.

The upper end of this latch plate is bent 60 over to form what I call a latch lip 18, which normally is seated in a transverse recess 19 formed in or applied to the con-

fronting face of the carrying plate 12, and normally a spring 20, see Figure 4, holds the plate in an upright position with its lip 18 in engagement with the recess 19 in the carrying plate 12.

The lower edge of the latch plate 15 as best shown in Figure 5, overlaps the inner ends of three spring-controlled push buttons, of which 20 is the central, 21 the right hand, and 22 the left hand, button.

Each of these buttons being normally held out by a spring 23, it is obvious that when any one of them is pressed inwardly its spring will be compressed and the latch plate 15 against which they bear deflected 80 so as to permit of the downward movement of the button housing 13.

A convenient form for in part mounting these push buttons is by means of what I call a button plate 24, see Figures 5 and 9, 85 through orifices in which the inner or operating ends of the buttons pass, and which is mounted within the lever housing as shown in Figure 7.

Looking at Figures 5 and 7, it will be noticed that the ends of all three of the push buttons bear against the latch plate 15, so that after the release of the latch lip 18 from its recess 19, by the pushing in of the middle button 20, the pushing in of 95 either of the side buttons 21 or 22 will cause the deflection or twisting about its pivot rod 16 of the latch plate 15.

This deflection is possible because the slots for the rod 16 in the ears 17 are not tight 100 fitting, and the result is that the twisting of plate 15, indicated in dotted lines in Figure 7, will make possible the passage of one of the button ends, that of 21 for instance, over the stop 25, or that of 22 105 over the stop 26.

Assuming all of the parts in the normal position represented in Figures 2 to 7 inclusive, and the button housing 13 in its uppermost position, the signal hand will be 110 set in the vertical position shown in full lines in Figure 11.

Assume, then, that it is desired to impart to said hand a quarter turn in the right-hand direction of Figure 11, the central button 20 will, as explained, first be pushed in to free the latch plate 15 and so permit of the downward movement of the housing 13 which, when the push button 21 is pressed in, will be continued until the end of the push button 21 encounters the stop 25, and the descent of the housing stopped.

When, thereafter, it is desired to give another quarter turn to the hand, the push button 22 will be pressed in to deflect or warp the latch plate to such extent that the button 21 can pass over the stop 25, and the housing 13 will then be pushed down until the button 22 encounters the stop 26, the result of which will be the stoppage of 125 130

the descent of the housing 13 and the imparting of a further quarter turn to the signal hand.

When it is desired to effect the last turn 5 of the signal hand, the button 21 will be pushed in to warp the latch plate 15 so that the button 22 will clear the button 26 and permit the pushing down of the housing 13 until it makes contact with the stop 27 10 at the bottom of the carrying plate 12.

The entire control of the housing is manual and its stoppage at the point necessary to give the desired position to the signal hand is due to the control of the push 15 buttons and their adjuncts as above described.

Having thus described my invention what I claim as new and desire to secure by Letters Patent, is:—

20 1. In a device of the character described,— a vehicle,—a signaling device on said vehicle,—a device under the control of the driver, which comprises a movable housing and push buttons carried by said housing,— 25 stops to be encountered by said push buttons to limit the movement of said housing,—and a flexible connection between said housing and said signaling device.

2. In a device of the character described,— 30 a vehicle,—a signaling device on said vehicle which is adapted to be moved into different positions,—a device under the control of the driver and mounted upon the steering column, which comprises a carrying plate, and a manually-operated housing 35 provided with a plurality of push buttons,—a plurality of stops within the range of movement of the push buttons, mounted upon the carrying plate, and adapted to control the stoppage of the movement of the housing,— 40 and a flexible connection between said housing and said signaling device.

3. In a device of the character described,— a vehicle,—a signaling device on said 45 vehicle which is adapted to be moved into different positions,—a device under the control of the driver and mounted upon the steering column, which comprises a carrying plate, and a manually-operated housing pro- 50 vided with a plurality of spring-controlled

push buttons,—a plurality of stops within the range of movement of the push buttons, mounted upon the carrying plate, and by the encounter of the push buttons adapted to control the stoppage of the movement of the 55 housing,—and a flexible connection between said housing and said signaling device.

4. In a device of the character described,— a vehicle,—a signaling device on said vehicle which is adapted to be moved into 60 different positions,—a device under the control of the driver and mounted upon the steering column, which comprises a carrying plate, and a manually-operated housing provided with a plurality of spring-controlled 65 push buttons,—a pivoted latch plate against which the inner ends of all of the push buttons bear so that any one of them can move it about its pivot,—a plurality of stops within the range of movement of the push buttons, 70 mounted upon the carrying plate, and by the encounter of the push buttons adapted to control the stoppage of the movement of the housing,—and a flexible connection between said housing and said signaling de- 75 vice.

5. In a device of the character described, a mechanism, in combination with the steering column, for operating a signaling device,—which comprises a carrying plate 80 secured to the steering column,—a housing manually movable longitudinally on said carrying plate,—a latch plate pivoted to said housing,—spring-controlled push buttons mounted in the housing and operative upon 85 the latch plate to tilt it into different positions,—stops upon the carrying plate adapted at the will of the driver to be encountered by push buttons on the carrying plate to limit the movement of the housing, 90 —a signaling device and a flexible connection between said device and said housing.

In testimony that I claim the foregoing as my invention, I hereunto sign my name this 12th day of January, A. D. 1923.

FRANK C. DREW.
